TEMPERATURE CONTROL MOLD

Filed Sept. 14, 1942

UNITED STATES PATENT OFFICE

2,420,003

TEMPERATURE CONTROL MOLD

Raymond J. Miller, Detroit, Mich., assignor, by direct and mesne assignments, to Miller Engineering Corporation, Detroit, Mich., a corporation of Michigan

Application September 14, 1942, Serial No. 458,265

20 Claims. (Cl. 22—113)

1

This invention relates to the art of casting and more particularly to a simple and economical mold to control the transfer of heat from molten alloy or metal to delay solidification of lighter molten sections, and to accelerate the solidification of heavier molten sections to reduce undesirable effects of shrinkage strains caused by the heavier sections of the casting solidifying and attempting to draw metal from lighter sections of the casting already solidified.

Cooling of a casting begins immediately upon the molten alloy or metal being poured into a mold, and when the temperature drops to a predetermined degree the molten alloy or metal solidifies to form the casting. Solidification of molten alloy or metal is accompanied by shrinkage or a reduction in volume due to contraction of the space between molecules of the alloy or metal upon passing from a liquid to the solid state.

The period of time required for molten alloy or metal to solidify depends upon the rate of heat transfer therefrom. Where the casting has sections of varying volume, the period of time required for solidification depends upon the ratio of the area of the cooling surface of the mold to the volume of the casting, and is influenced by the rate of heat transfer over various sections of the mold.

In the formation of castings having sections of varying contour, the lighter molten sections have a greater ratio of surface area to volume in contact with the mold cavity than do the heavier sections. The thinner sections therefore cool more rapidly and will solidify while the heavier sections of the casting are still molten.

In castings having light or thin sections between heavy sections and the feeder, the thin sections tend to solidify while the heavy sections remain molten. As the thin sections jell or solidify they form a point of anchorage for the molten alloy or metal and also cut off the heavy sections from the shrinkage compensating supply of molten alloy or metal from the feeder.

The supply of molten metal or alloy in the feeder chamber to compensate for reduction in volume due to shrinkage frequently solidifies before the heavier sections of the casting. When this happens the heavier sections are cut off from the supply of molten alloy or metal for com-

2

pensating for shrinkage. When solidification of the heavier sections of the casting occur shrinkage strains of considerable magnitude are set up in the casting because of the isolation of the heavier sections from the supply of molten alloy or metal to maintain the mold completely filled.

In order to prevent shrinkage strains in castings it is desirable that the feeder be accessible to and remain in communication with the entire casting to supply molten alloy or metal to maintain the mold completely filled with alloy or metal until the entire casting has completely solidified. This may be most easily effected by controlling the cooling of the casting to cause all sections of the casting to cool progressively from points remote from the shrinkage compensating supply of metal in the feeder chamber towards said chamber. A continuous supply of molten alloy or metal will therefore be available at all times to maintain the mold completely filled and prevent the introduction of shrinkage strains caused by one portion of the casting attempting to draw metal from surrounding solidified portions.

To obtain this desirable progressive cooling in castings having varied contours and eliminate the undesirable effects of shrinkage strains it is necessary to dissipate heat more rapidly from the larger or thicker sections and to retard the transfer of heat from the thin or lighter sections.

When molten alloy or metal is poured into a mold to form a casting, an envelope or skin is formed on the outer surface of the molten substance by contact with the air or gases within the mold. If the molten alloy or metal is poured into the mold slowly and at a substantially constant rate the envelope or skin can be progressively expanded to surround the entire casting and maintained throughout the entire casting until the solidification occurs substantially progressively or uniformly over the entire casting.

This envelope or skin formed on the outside of the molten alloy or metal contacts the surface of the mold cavity and is maintained during cooling of the molten alloy or metal. The resulting casting has a fine textured smooth surface free from roughness due to a breaking of the surface skin or envelope. By effectively maintaining the feeder open until the entire

casting solidifies, a more solid casting having higher physical properties less susceptible to warpage results.

In the so-called Capaco process of casting as disclosed in Patent No. 2,201,037, issued May 14, 1940, plaster is used as the mold body. During the formation of the plaster mold an excess of moisture is present and the plaster mold is thereafter subjected to a drying process whereby virtually all of the moisture is driven off from the mold. The resulting mold is relatively porous and has a very smooth glass-like internal surface.

Molten alloy or metal is poured directly into the plaster molds and due to the porosity of the molds, gases formed during the pouring, cooling and solidifying process, and entrained air may readily escape through the body of the mold forming substance. A fine grained homogeneous casting having a smooth surface finish results.

The rate of heat dissipation from a mold formed of low heat conducting material particularly of the so-called plaster type, varies almost in direct proportion to the external surface area of the mold to the unit volume of the casting to be formed. By increasing the ratio of external surface area to the volume of the mold cavity over the thicker or heavier sections of the casting the rate of heat dissipation may be accelerated. Likewise by reducing the ratio of the external surface area to the volume of the mold cavity the rate of heat dissipation from the thinner portions of the casting may be retarded.

No means has heretofore been available to vary the rate of heat transfer from castings formed in low heat conducting materials such as plaster molds. The use of the so-called plaster molding process has therefore been limited to objects having substantially uniform cross section or objects wherein shrinkage strains caused by uneven cooling of various sections of the castings would not be unduly objectionable. In order that this process may be used in the casting of articles having varied cross sections it is necessary that some means be available to compensate for variation in thickness of the sections of a casting to permit progressive cooling of all sections of the casting towards the point of feed.

My copending application, Serial No. 455,862, filed August 24, 1942, discloses a plaster mold wherein the ratio of the external surface area of the mold is substantially proportionate to the volume of the mold cavity throughout. These temperature control molds may be formed between a pattern of the article to be cast and a contour forming member for the external surface of the mold. An external mold contour forming member must of necessity be made for each article to be cast. While excellent results can be accomplished by the use of that method, the expense involved in making the mold former is disproportionately high where only a few castings of an article are desired.

An object of this invention resides in the provision of a simplified plaster mold forming member to facilitate the formation of plaster molds having external surface area substantially proportionate to the volume of the mold cavity throughout.

Another object of the invention is to provide a plaster mold forming member having movable pegs adapted to be positioned in varied spaced relation to a pattern to form a plaster mold having a substantially proportionate ratio of external surface area to the volume of mold cavity.

A further object of this invention resides in the development of a simplified method and apparatus whereby the heat transfer from castings may be controlled to provide substantially progressive cooling towards the feeder over the entire area of the casting.

Another object of the invention resides in the provision of a simplified method for controlling the rate of heat transfer from a casting by accelerating the rate of heat transfer from thicker or heavier sections and delaying the rate of heat transfer from thinner or lighter sections of the casting.

A further object is to provide a relatively porous mold having a progressively decreasing ratio towards the feeder, of external surface area to the volume of sections of varying contour of the casting to be formed to control the rate of heat transfer from molten alloy or metal to give progressive cooling towards the feeder.

Yet a still further object of the invention resides in the provision of a low heat conducting mold having an apertured surface to increase the external surface area and hence the rate of heat transfer of portions of the mold surrounding thicker or heavier sections of the casting.

Yet another object resides in the provision of an economical method of forming temperature control mold sections having cooling surface area proportionate to the cross section of castings throughout to control the rate of heat transfer from sections of varied contour.

A further object is to provide a simple and efficient method of holding aperture forming members in a desired spaced relation to form a mold having varied surface area.

Another object is to provide a plaster temperature control mold formed of low heat conducting material having a substantially constant volume of mold forming substance throughout to permit moisture to escape uniformly over the mold surface to insure substantially uniform drying of the mold.

Other objects and advantages of this invention will be apparent from the following detailed description considered in connection with the accompanying drawings, submitted for purposes of illustration only, and not intended to define the scope of the invention, reference being had for that purpose to the subjoined claims.

In the drawings wherein similar reference characters refer to similar parts throughout the several views:

Fig. 1 is a sectional view of a typical article to be formed.

Fig. 2 is a sectional view of a pattern for forming the article of Fig. 1 having a temperature control mold former superimposed thereon.

Fig. 3 is a sectional view of the temperature control forming mold for making a plaster mold having variable external surface area to provide different rates of heat transfer over various portions thereof.

Fig. 4 is a plan view of the former illustrated in Fig. 3.

Fig. 5 is a sectional view of a temperature control plaster mold having a casting therein.

Fig. 6 is a sectional view illustrating a modified form of holding mechanism for the recess forming members.

Fig. 7 is a fragmentary plan view of a mold embodying recesses of a different shape.

Fig. 8 is an elevational view showing a tapered recess forming member.

Referring now to the drawings, Fig. 1 is illus-

trative of any article 20 which may be formed by a casting operation. The article 20 may, for example, be a flywheel having a thick rim 22 and axially extending flanges 24 on a hub member 26.

The hub and rim are interconnected by a plurality of radially extending spokes 28 of relatively small cross sectional area in proportion to the cross sectional area of the rim 22. The ratio of the volume to the external surface area of the rim 22 and flanges 24 of the article 20 is much greater than the ratio of the volume to the external surface area of the spokes 28. The ratio of the B. t. u. or heat content of large molten sections in proportion to the area of the mold cavity is therefore higher than the B. t. u. or heat content of the smaller molten sections in proportion to their area in contact with the mold cavity.

In the casting of the article 20, such as the flywheel, a feeder would preferably be positioned at one side of the rim 22 to supply molten alloy or metal through the rim 22 and spokes 28 to the hub 26.

If no means are provided for controlling the rate of heat transfer from the molten alloy or metal of which the casting is formed, the spokes 28, having greater external surface area in proportion to the B. t. u. or heat content of their molten metal will be subjected to more rapid cooling and will reach the solidification point before the rim 22 and hub member 26 wherein the ratio of the B. t. u. or heat content to the mold cavity is considerably higher.

After the alloy or metal forming the spokes 28 cools to a substantially predetermined point it will jell and solidify and the flow of molten alloy or metal to the hub 26 will be cut off. As the mass of alloy or metal forming the hub 26 solidifies it shrinks or contracts and attempts to draw metal from the spoke forming sections 28.

Since the supply of molten metal to the hub 28 is effectively interrupted by solidification of the alloy or metal forming the spokes, shrinkage of the hub 28 upon solidification results in a force being exerted to draw metal through the spoke forming segments and shrinkage strains of considerable magnitude result. The resulting casting is not homogeneous or solid and does not possess the desired degree of strength. The casting is pre-stressed and is susceptible of warping, and in any ensuing machining operations or use whereby strains would be relieved, further warping results.

Fig. 5 illustrates a temperature control mold 30 having upper and lower sections 32 and 34. The mold 30 is preferably formed of a low heat conducting porous moldable substance, or a substance such as plaster susceptible of being rendered porous after being formed.

The rate of heat dissipation of such material by radiation is almost directly proportional to the ratio of the external surface area of the mold to the volume of the mold cavity.

The cooling effect of the mass of the body portion of a low heat conducting material such as a plaster mold by conduction is substantially in inverse proportion to the volume of the metal of the casting at any point.

In order to effect uniform cooling of sections of varied volume of the article to be cast in the mold 30, the ratio of the heat radiating surface of the mold should substantially be in direct proportion to the volume of the article to be cast. By progressively decreasing the ratio of the external mold surface to the volume of the mold cavity

towards the feeder progressive cooling towards the point of feed may be accomplished.

Controlled cooling may thus be effected whereby all parts of the casting cool progressively towards the feeder, and the feeder and the lighter sections of the casting are maintained open until the heavier or thicker sections of the casting solidify. Since a constant supply of molten metal is available from the feeder, shrinkage of the metal will merely draw more molten alloy or metal from the shrinkage compensating feeder chamber and shrinkage strains will be effectively avoided.

While the mold 30 may be formed of upper and lower sections 32 and 34, in making temperature control molds 30 for more complicated castings additional sections may be employed. These additional sections may be vertically spaced and may be of triangular, rectangular or of any other desirable shape adapted to interlock to form the desired temperature control mold contour.

The external surface of the temperature control mold 30 may, for example, be formed with a plurality of relatively closely spaced recesses or apertures 36 terminating close to the sections of larger volume of the article 20, such as around the rim 22 and flanges 24 and over the hub 26 respectively, to increase the ratio of the external surface area of the mold to the volume of the mold cavity to permit rapid transfer of heat from these portions of the heavier sections of the casting. The recesses 36 should terminate a sufficient distance from the article to be cast to provide the mold with sufficient strength to adequately support the alloy or metal 40 poured into the mold 30 to form the article 20.

The mold 30 over the spokes 28 may be relatively thick and provided with fewer recesses or apertures 36 to decrease the ratio of the cooling surface area of the mold to the volume of the mold cavity to retard the flow of heat from the alloy or metal 40 of which the spokes 28 are formed.

The spacing and depth of the holes or recesses 36 in the mold forming substance over sections of varying contour of the article 20 to be cast may be proportioned to provide a mold 30 having a substantially constant or progressively decreasing ratio towards the feeder of external surface area to the volume of the mold cavity to produce substantially uniform or progressive cooling of the casting.

The size of the mold 30 is dependent on the size and contour of the article 20 to be cast, the amount of heat to be dissipated from the alloy or metal of which the article 20 is formed. The rate of heat conductivity of the substance of which the temperature control mold 30 is formed, the rate of heat transfer from the surface of the mold 30 to the atmosphere and other factors.

The lower section 34 of the temperature control mold 30 may be supported during the casting operation at its edges to permit air to circulate freely into the apertures 36. If the article being formed is so large that the mold could not be supported at its edges it may be supported on a suitable framework or on downwardly extending feet or flanges positioned to underlie the heavier portions of the article to be cast.

The upper section 32 of the mold 30 may be formed with a riser and feeder member 42. The feeder and riser forming member 42 is formed with a feeder chamber 44 to supply molten alloy or metal through a passageway 46 to compensate for shrinkage of the casting. The feeder 44

is surrounded by a suitable mass 48 of the substance from which the mold 30 is formed to decrease the ratio of external surface area to volume of the mold cavity at this portion to prevent solidification of alloy or metal in the feeder chamber 44 until the remainder of the casting has solidified.

The spacing and depth of the apertures 36 in the temperature control mold 30 may be proportioned in such a manner that solidification of the alloy or metal 40 forming the casting will start at a point remote from the feeder chamber 44 and flow progressively towards the riser.

The sections 32 and 34 of the temperature control mold 30 may be formed between male production patterns of the article to be cast and suitable contour forming members superimposed on the pattern.

As illustrated in Fig. 2, a male production pattern 50 is suitably attached to a flask 52 having side wall members 54. The flask may be of any desired contour such as round, rectangular, etc., to accommodate the pattern 50. A cover plate 56 having a plurality of spaced apertures 58 therethrough may be superimposed on the side walls 54 of the flask 52, and may be located in a predetermined angular relation thereto by suitable dowel pins 60.

The apertures 58 may be of uniform size and may be closely spaced as illustrated in Fig. 4, and are adapted to receive vertically movable members or pins 62 adjustably mounted therein to vary the distance from the bottom ends 64 of the members or pins relative to the cover plate 56.

Any suitable means may be provided to maintain the members 62 in any vertically adjusted position relative to the plate 56. An apertured resilient sheet 66, such as a sheet of rubber, may be attached to the cover plate 56 to engage the pins 62 and hold them in any vertically adjusted position to which they are moved.

Ring springs 67 positioned in slots 69 in the plate 56 may also be employed to engage the recess forming members 62 to hold them in any vertically adjusted position to which they are moved as illustrated in Fig. 6.

The recess forming members 62 may be of any desired contour in cross section to provide recesses of varied configuration such for example as the hexagonal recesses 71 illustrated in Fig. 7. As illustrated in Fig. 8 the recess forming members 73 may be tapered to provide the mold surface with varied external surface area and to facilitate the dissipation of moisture and heat from the mold during the drying of the mold and the cooling of the casting.

In the formation of the sections of the mold 30, any suitable mold forming substance such as low heat conducting plaster may be introduced into the space within the flask 54 to cover the pattern 50 to a desired height on the pins 62. The cover plate 56 may be assembled on the flask 52 having the pattern 50 therein. The pins 62 may then be pushed downwardly into contact with the surface of the pattern 50. The cover plate 56 may then be elevated and a spacer 68 interposed between the side walls 54 of the flask and the cover plate 56 to elevate the lower ends 64 of the pins 62 a predetermined distance above the surface of the pattern 50. Spacers 68 of different thickness may be provided for use in forming temperature control molds for various articles.

The ratio of the external surface area to the volume of the mold cavity and hence the rate of cool-

ing of the casting may be controlled by varying the height of the lower ends 64 of the pins 62 above the pattern 50. For example, the mold 30 over the heavier sections 22, 24 and 26 of the article 20 to be cast, may have many closely spaced apertures 36 terminating close to the mold cavity. The mold 30 over the lighter or thinner sections 28 of the article to be cast may have relatively few apertures 36 terminating a greater distance from the mold cavity to reduce the ratio of the surface area to the volume of the mold substance and delay the transfer of heat from the lighter portions of the mold.

After the recess forming members 62 have been adjusted vertically to vary the external mold surface to accelerate the transfer of heat from heavy sections of the casting and to retard the transfer of heat from the light sections of the casting, the mold forming substance may be introduced into the flask through an opening 70, air being permitted to escape through another of these openings. The quantity of plaster or other mold forming substance employed is dependent on the nature and size of the casting to be formed, the rate of heat transfer, etc.

The portions of the pins or pegs 62 projecting into the mold forming substance may be coated with any suitable parting material 72 to facilitate separation of the pegs from the mold forming substance.

If desired the cover plate 56 and the resilient sheet 66 may be transparent to such an extent as to enable the molder to observe the position of the lower ends 64 of the pins 62 relative to the pattern 50. Where the pins 62 are of uniform length the outline of the pattern 50 will be reproduced at the upper ends of the pins 62 projecting above the cover plate 56 to aid the molder in making the necessary adjustments. The diameters of the pins may be varied if desired to give more definite control of the external surface area of the mold.

The composition of the plaster or other mold forming substance is preferably such as to form a relatively porous mold structure whereby gases formed during the casting operation and entrained air may readily escape through the body of the mold. This relatively porous plaster mold structure may be achieved by initially mixing the plaster forming ingredients with somewhat of an excess of moisture and thereafter drying the mold to drive off virtually all of the moisture.

The mold 30 is preferably such as to adequately support the casting when poured but does not possess sufficient strength to resist the forces to which it is subjected when the casting shrinks upon solidification. Shrinkage of the casting may, therefore, crack or break up the mold and thus avoid the introduction of shrinkage strains within the casting.

The upper section 32 of the mold 30 may be interlocked with the lower mold section 34 by means of circumferentially extending interlocking flanges 74, and the sections 32 and 34 may be held together by means of suitable clamps 76.

In the casting of an article 20 in the temperature control mold 30, molten alloy or metal 40 is introduced through the opening in the feeder positioned at any convenient place as at one side or in the middle of the mold. The molten alloy or metal 40 flows through the controlled gate 48 into the space within the mold 30 and completely fills the space within the mold 30.

Gases formed upon contact of the molten alloy or metal 40 with the internal surface of the mold

38, and entrained air in the mold are readily dissipated through the mold forming substance. Sprues are therefore unnecessary and a reaction is set up between the inner surface of the mold and the liquid alloy or metal whereby a very smooth surface results on the casting.

The upper and lower sections 32 and 34 of the mold 30 dissipate heat from the molten metal 40 substantially uniformly over the entire area of the casting. The increased external surface area of the mold due to the presence of the recesses or holes 36 coupled with the sections of relatively thin mold section over heavy portions of the casting permit rapid dissipation of heat from the heavier sections of the casting, and the walls of the mold having less apertures tend to retain the heat in the thinner sections of the casting, such, for example, as the spokes 28.

Virtually the entire casting cools progressively or simultaneously. The controlled supply gate 46 and the feeder chamber 44 provide an ample supply of molten metal to compensate for contraction of metal upon solidification. The thinner spoke forming sections remain molten during cooling of the heavier sections and all parts of the casting solidifies progressively towards the feeder or simultaneously.

If desired, air may be circulated over the mold sections to assist in the dissipation of heat from the mold. The cooling air may be controlled as to direction to subject only a portion of the mold 30 to the cooling action, to give more accurate and positive control over the cooling of the casting. The temperature of the air directed over the mold 30 may also be controlled to produce the desired cooling of various portions of the casting to insure uniform or progressive solidification of the casting.

When a plaster mold is subjected to a drying action the entrained moisture in the mold is transferred to the surface of the mold by capillary attraction, and it is transferred to the atmosphere from the external surface of the mold. Large masses of solid plaster delay the transfer of moisture to the surface, whereas small sections or sections having a larger ratio of surface area to volume readily transfer moisture to the surface for dissipation to the atmosphere. In molds having wide variation in sections, unequal drying action results and the lighter or thinner sections are likely to become burned and crack before the heavier or thicker sections have had an opportunity to dry.

These difficulties can be overcome by somewhat increasing the number or the depth of the recesses over heavy sections of the article to be cast to permit the use of a sufficient number of recesses in the heavier mold sections, positioned to overlie lighter sections of the article to be cast. The use of a larger number of recesses increases the ratio of the surface area to the volume of the mold forming substance to break up large solid masses of mold forming substance which would delay the transfer of moisture from the mold during the drying operation. Uniform drying of the mold may thus be effected, and since these recesses are formed in the mold forming substance they have a desirable effect on dissipation of heat from the casting. Accurate control of the dissipation of heat from the casting may thus be effected.

I claim:

1. A temperature control mold forming member comprising a flask having a pattern therein, a plate superimposed on the flask and having

a plurality of closely spaced apertures therein, a plurality of recess forming members movably mounted in said apertures, and resilient means to maintain the recess forming members in any adjusted position.

2. A temperature control mold forming member comprising a plate having closely spaced apertures therein, members extending through and movable in the apertures, and resilient means to hold the members in any position to which they may be moved.

15 3. A temperature control mold forming member comprising a flask having a pattern therein, a plate superimposed on the flask and having a plurality of closely spaced apertures therein, a plurality of pegs extending through said apertures and movable relative to the plate, and resilient means associated with the plate to hold the pegs in any adjusted position to which they may be moved.

20 4. A temperature control mold forming member comprising a plate having closely spaced apertures therein, pins extending through and movable in the apertures, and resilient means carried by the plate to hold the pins in any vertical position to which they may be moved.

25 5. A mold forming member comprising a flask having side walls, a pattern detachably connected to the flask, a recess forming member supporting 30 plate carried by the side walls of the flask, locating means between the plate and flask, a plurality of spaced vertically movable recess forming members carried by the plate, resilient means to hold the recess forming members in any adjusted 35 position, a spacer adapted to be interposed between the flask and the plate, and locating means associated with the spacer to maintain alignment between the flask and plate.

40 6. The method of making a temperature control mold comprising superimposing on a pattern of an article to be cast a member having closely spaced movable recess forming members, adjusting the recess forming members to contact the surface of the pattern, separating the recess forming members from the pattern by introducing a spacer beneath the member, withdrawing recess forming members over light sections of the casting, and applying to the exposed surface of the pattern and pins a substance capable of being rendered substantially porous to provide a mold 45 having a substantially constant ratio of external surface area to the volume of the article to be cast.

50 7. The method of forming a temperature control mold for castings having varying contours comprising superimposing on a pattern of the article to be cast a plate having closely spaced vertically movable pegs, adjusting the pegs vertically relative to the pattern in proportion to variations of volume of the casting, and introducing plaster around the pattern and downwardly projecting ends of the pegs to form a temperature control mold having large external surface area surrounding heavy sections of the article to be cast and relatively less external surface area over lighter sections of the article to be cast.

55 8. The method of making a plaster temperature control mold comprising superimposing on a pattern of an article to be cast a plate having closely spaced adjustable recess forming members, adjusting the recess forming members to contact the surface of the pattern, separating the recess forming members from the pattern by introducing a spacer beneath the plate, withdrawing 60 recess forming members over light sections of

75 recess forming members over light sections of

the casting, applying plaster to the exposed surface of the pattern and recess forming members to form a temperature control mold having a ratio of surface area to volume substantially proportional to the ratio of surface area to volume of the article to be cast, and drying the plaster mold to dispel moisture.

9. A low heat conducting mold former comprising a pattern, a frame surrounding the pattern, a member having mold recess forming members superimposed on the frame to form spaced recesses in the external surface of the mold, manually operable means to selectively vary the spacing of the recess forming members from the pattern, and means to hold the recess forming members in any adjusted position.

10. A mold former comprising a flask having a pattern therein, an apertured plate having mold recess forming members superimposed on the pattern to form spaced recesses in the external surface of the mold to reduce the ratio of the mass of the mold forming substance to its external surface area throughout to facilitate the transfer of moisture to the surface of the mold and accelerate drying of the mold, means to selectively vary the spacing of the recess forming members from the pattern, and means to hold the recess forming members in any adjusted position.

11. The method of forming a non-permanent mold formed of low heat conducting material comprising superimposing on a pattern a mold contour former having closely spaced parallel mold recess forming members of generally circular cross-section for shaping the external surface of the mold to provide a mold forming space substantially in inverse proportion to the volume of sections of varying contour of the casting to be formed, filling said space with a low heat conducting mold forming substance, separating the mold from the pattern and contour former, and thereafter drying the mold.

12. A non-permanent temperature control mold formed of low heat conducting material to prevent the formation of shrinkage strains in a casting having a feeder and sections of varying cross-sectional area, the external surface area of the mold being contoured with closely spaced generally circular recesses extending substantially perpendicularly to the external surface of the mold so arranged as to dispose the mass of the mold material substantially in inverse proportion to the cross-sectional area of the casting throughout to vary the rate of the dissipation of heat by conduction from sections of varying cross-sectional area of the casting to prevent the formation of solidified sections between the feeder and a portion of the casting.

13. A non-permanent mold formed of low heat conducting material for forming a casting having sections of varying cross-sectional area comprising a body portion having an external surface provided with substantially perpendicularly extending generally circular recesses to increase the ratio of the surface area of the mold to the mass of the mold forming substance to reduce the distance moisture must travel to reach the external surface of the mold to accelerate drying of the mold without introducing mold shrinkage strains.

14. A non-permanent temperature control mold formed of low heat conducting material comprising a body portion having a casting cavity and including a substantially flat external surface having a plurality of recesses of generally circular cross section extending inwardly toward the casting cavity substantially perpendicularly to the flat

external surface of the mold so arranged as to vary the mass of the mold forming material substantially in inverse proportion to the volume of sections of varying cross-sectional area of the casting to be formed.

15. A temperature control mold having a casting cavity for the reception of molten alloy or metal to form a casting having sections of varying cross-sectional area comprising a dried mold formed of low heat conducting material having closely spaced recesses of generally circular cross section extending substantially perpendicularly from the external surface of the mold to points adjacent the casting cavity over sections of the casting of large cross sectional area to increase the ratio of the external surface area of the mold to the cross sectional area of the casting and permit the rapid transfer of heat from heavy portions of the casting, and spaced recesses extending substantially perpendicularly from the external surface of the mold to points progressively more remote from the casting cavity over sections of the casting of progressively smaller cross sectional area to progressively increase the ratio of the external surface of the mold to the cross sectional area of the casting but to a lesser degree than the recesses in the mold over the sections of the casting of greater cross section to retard the transfer of heat from light portions of the casting.

16. A temperature control mold having a casting cavity for forming a casting having sections of varying cross-sectional area comprising a body portion formed of low heat conducting material having closely spaced generally circular recesses extending substantially perpendicularly from the external surface of the mold toward the casting cavity to points adjacent the casting cavity where the cross-sectional area of the casting is large and to points more remotely spaced from the casting cavity where the cross sectional area of the casting is small.

17. A non-permanent mold formed of low heat conducting material comprising a body portion having a casting cavity and a plurality of closely spaced parallel recesses of generally circular cross-section extending inwardly from the external surface of the mold toward the casting cavity to provide a honeycomb-like structure to reduce the mold forming material required and to facilitate the drying of the mold by reducing the distance moisture must travel to reach the surface of the mold to be expelled.

18. A mold former comprising a pattern, a housing surrounding the pattern, and a plurality of mold recess forming members carried by the said housing, said members being shiftable to selectively vary the heat dissipating qualities of the mold material.

19. The method of making a non-permanent mold formed of moisture containing material, which comprises forming in said material, while it is still wet, a plurality of recesses to control the heat dissipating properties of the material, removing the recess forming members, and thereafter subjecting said material to a drying action to transfer to the outer surfaces of the material the moisture entrained therein, the said drying action being accelerated by virtue of the recesses having been formed in the material prior to such drying action.

20. The method of controlling heat dissipation from a mold material containing liquid contoured to provide a casting cavity, which method includes the steps of inserting a plurality of mem-

13

bers in said material to different depths to form closely spaced heat flow paths therein overlying and extending along the casting cavity to regulate the lengths of the heat flow paths through said mold material and to vary the heat dissipating properties of the mold in accordance with the spacing of the heat flow paths, and thereafter removing said members.
